UNITED STATES PATENT OFFICE.

FRANK S. CLEGHORN, OF BROOKLINE, AND HARRY E. BARBER, OF BOSTON, MASSACHUSETTS.

RADIATOR-SUPPORT.

1,201,938.

Specification of Letters Patent. Patented Oct. 17, 1916.

Application filed February 25, 1916. Serial No. 80,548.

To all whom it may concern:

Be it known that we, FRANK S. CLEGHORN and HARRY E. BARBER, citizens of the United States, and residents of Brookline 5 and Boston, respectively, in the counties of Norfolk and Suffolk, respectively, State of Massachusetts, have invented an Improvement in Radiator-Supports, of which the following description, in connection with 10 the accompanying drawings, is a specification, like characters on the drawings representing like parts.

This invention relates to radiator supports and the purpose is to provide a support which will accommodate a considerable degree of expansion and contraction of the radiator under changes of temperature.

Specifically we aim to provide a bracket support which, while applicable to radiators of various forms, is particularly adapted to hold suspended adjacent a vertical wall a radiator of the type commonly known as "wall radiators". Such radiators are usually formed as a kind of grille of tubes or pipes and they frequently extend for considerable distances in large rooms or corridors. The longitudinal expansion is therefore great and requires special consideration.

Our invention will be best understood by reference to the following description taken in connection with the accompanying drawings, wherein:

Figure 1 is a view of a radiator of the wall type held by a pair of brackets constructed according to our invention; Fig. 2 is a side view of a bracket embodying our invention, a part of the radiator being shown in dotted lines; Fig. 3 is a face view 40 of the bracket; Fig. 4 is a top plan view, the radiator tubes or pipes being shown in section; and Fig. 5 is a view similar to Fig. 2 showing a modified form of construction.

Our invention is allied to those described 45 in our Patents 1,175,706 and 1,175,707 dated March 14, 1916, and we will be somewhat brief in our description in so far as the form illustrated includes features of construction which were embodied in the structures shown in those patents.

Referring to Figs. 1 and 4, it will be seen that the one form of our invention contemplates the use of brackets A which are attached to a vertical wall and which sustain a radiator B by being secured thereto

preferably along a comparatively narrow vertical zone near its base. A convenient form of this bracket A consists of a relatively small base plate 2 which provides what is substantially a one-point contact 60 with a vertical wall. This base plate is attached to the wall by a bolt 3 which is preferably disposed in a slot 4 to provide for vertical adjustment of the bracket so that it may be brought into accurate horizontal 65 alignment with another. Extending from the plate 2 is a substantially horizontal supporting arm or rest 5 which is adapted to engage the bottom tube of the radiator or some other horizontal portion thereof and 70 hold the radiator suspended. We have herein shown a lug 6 on the arm 5 to assist in positioning the radiator thereon. Means are provided to retain the radiator on the rest 5 and to keep it in a vertical position, 75 such means being exemplified in the embodiment of the invention here shown by the vertical supporting member or plumbing column 7 which extends vertically from the arm 5 in spaced relation to the base 80 plate 2. In other words, in the embodiment of the invention herein illustrated the outer part of the arm 5 and the supporting member 7 form an angular receiving portion which approximates in form the lower part 85 of the radiator and which is connected by the neck 5' to the base plate 2. When the bracket is in position the radiator is supported and held spaced from the wall by 90 the neck 5' and the space behind it is obstructed to a minimum degree and there are no widely spaced fastenings to exert a twisting or crushing strain on the plaster of the wall. The radiator is placed in position on the rest 5, against the lug 6 if one 95 is used, and held vertically by being clamped toward or stayed to the member 7, preferably at an intermediate point in its height, in a manner to be hereafter described.

When the radiator is subjected to extremes of temperature the various pipes or tubes thereof expand and contract and in particular a sliding movement over the arm 5 is developed. In order to permit this movement to take place freely, we preferably arrange the clamping means which stays the radiator to the member 7 so as to permit this movement. For this purpose the member 7 may carry an open frame 8, best 105

shown in Fig. 3, which furnishes bearings for a guide or track 9 here shown as a round threaded rod or screw extending across or bridging the frame 8. This guide 9 furnishes a bearing for the slide block 10 which may move thereon freely within the limits of the frame and to which the radiator is stayed by means of the bolts or screws 12 and 13. These screws 12 and 13 provide 10 abutments adjustable to cause the radiator to fulcrum on the arm 5 so as to bring it to the exact vertical position irrespective of the original angular position of the bracket as a whole and which clamp the radiator 15 between them. To this end we provide the screw 12 adjustable from the front of the radiator between pipes thereof and engaging these pipes at the rear side and forming an abutment against which the radiator 20 may be clamped by the screw 13 which carries the washer block 14 engaging the pipes on the outer side. This clamping means is similar to that described in our Patent No. 1,175,707 above referred to and for a fuller 25 explanation thereof we refer thereto.

To adjust the radiator in position it is placed on the arm 5 and pressed backwardly against the head of the screw 12. The screw 12 is then adjusted by means of a suitable 30 tool such as a screw driver, which may be extended between adjacent vertical pipes of the radiator, until the radiator is brought to the exact vertical. It is then clamped into position by the screw 13. We have 35 herein shown the block 10 as provided with rounded ends 11 to permit it to turn freely on the guide 9 so that it will not bind in the frame 8 if the screws 12 and 13 are unevenly tensioned. When the radiator is 40 thus in position and is subjected to a considerable rise in temperature it will tend to expand and this expansion will be particularly marked longitudinally in view of the proportions of the radiator (see Fig. 45 1). The lowermost part of the radiator will slide on the rest 5 and the block 10 will move freely along the guide 9 and permit this longitudinal movement without imposing strains on the radiator or on the support 50 and without disturbing the adjustment to the vertical of the radiator.

If desired suitable anti-friction means may be provided to facilitate the sliding movement of the radiator on the arm 5. 55 For example, in Fig. 5 we have illustrated the arm as formed with a roller 5^a, preferably of hour-glass form to fit the bottom of the ordinary type of wall radiator, which roller is journaled in any suitable manner 60 as by means of the tap bolt 5^b which constitutes the outer part of the arm 5.

By the use of our invention the radiator is securely held but allowed sufficient lost motion to obtain the best results. At the 65 same time the fastenings are small and of

minimum weight. It is also possible to sustain the radiator by means of one row of fastenings and it is not necessary to attempt the difficult feat of adjusting four supports as it will be seen that all that is necessary is to align the supporting arms 5 as the clamping devices 10 and 11 do not engage beneath any part of the radiator and their precise vertical position is immaterial. The strains of longitudinal expansion are taken up by the motion provided for by the sliding blocks 10 and the effect of other warping and twisting strains is minimized because the brackets have what is substantially one-point contact with the wall through 75 the small base plates 2. A great deal of the radiator above the clamping screw 12 is, as a matter of fact, free to come and go at will without imposing any strain on the 80 wall fastenings.

While we have shown one specific form of our invention and described it in considerable detail the precise mechanical design of our device is not of primary importance although we prefer the form here- 90 illustrated. It may however be considerably varied without departing from the spirit of our invention and

What we do claim and desire to secure by Letters Patent is:

1. A support for radiators comprising a suspending arm to receive a horizontal part of the radiator and a supporting member presented to the back of the radiator including a frame, a guide bridging said frame, a block slidably and rotatably mounted on said guide and devices supported by said block to stay the radiator thereto and adjustable individually respectively to move the radiator from and toward the same.

2. A support for radiators comprising a suspending arm to receive a horizontal part of the radiator, a supporting member presented to the back of the radiator, a slide block held thereby in a plane parallel to the radiator and free for horizontal movement therein and means to stay the radiator to said slide block.

3. Supporting means for radiators comprising a bracket arm for suspending the radiator, a second arm disposed adjacent the side of the radiator, extensions on said arm providing bearings for a horizontal guide rod, an apertured block slidable on said rod and screw means tapping said block for staying the radiator thereto and holding the same upright on said bracket arm.

4. A supporting bracket for radiators comprising a suspending arm to receive a horizontal portion of the radiator, a substantially vertically disposed member presented to the back of the radiator and means to clamp said radiator and adjust it toward and from said member, said means being

carried by and having horizontal play on said member.

5. A support for radiators comprising a suspending arm to receive a horizontal part of the radiator, a supporting member presented to the back of the radiator and devices carried by said member with freedom of play in the horizontal direction only serving to stay the radiator to said support-

ing member to sustain the same upright 10 on said arm and adjustable individually respectively to move the radiator from and toward the supporting member.

In testimony whereof, we have signed our names to this specification.

FRANK S. CLEGHORN.
HARRY E. BARBER.
